CLAIM

The ornamental design for a camera stabilizing support, as shown and described.

DESCRIPTION

FIG. 1 is a rear perspective view of a camera stabilizing support in an operational position showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a rear perspective view of the camera support disclosed in FIG. 1, in a folded position adapted for shoulder use;

FIG. 9 is a left side elevational view thereof;

FIG. 10 is a right side elevational view thereof;

FIG. 11 is a top plan view thereof; and,

FIG. 12 is a bottom plan view thereof.
